UNITED STATES PATENT OFFICE.

WALTER B. FLOYD, OF COLUMBUS, OHIO, ASSIGNOR TO THE BONNEY-FLOYD COMPANY, OF COLUMBUS, OHIO, A CORPORATION OF OHIO.

GRINDING-MILL ROD.

Application filed December 18, 1924. Serial No. 756,855.

This invention relates to a fabricated grinding mill rod, and has for its primary object the provision of a rod constructed or formed with the end in view of providing efficient and prolonged service and formed so that replacements may be made after the parts have been worn to a predetermined extent.

Another object of the invention resides in the provision of a rod of the type aforesaid wherein is provided an exterior member having high abrasive resistant surfaces, which member is capable of being renewed from time to time as wear takes place.

15 A further object of the invention resides in a grinding mill rod consisting of an axially extending rod or core upon which is mounted a plurality of separable sleeves, the mounting of the sleeves on the core being so arranged that relative rotation between the sleeves and rod is prevented but the sleeves are capable of being longitudinally removed from the core upon the release of fastening devices which ordinarily function 20 to prevent such longitudinal movement.

For a further understanding of the invention reference is to be had to the following description and the accompanying drawing, in which:

30 Figure 1 is a side elevation of a grinding mill rod constructed in accordance with the present invention.

Figure 2 is a vertical sectional view thereof,

35 Figure 3 is a transverse vertical sectional view,

Figure 4 is a detail view of the core,

Figure 5 is a detail view of one of the sleeves constituting the rod, and

40 Figure 6 is a detail view of a modified form of sleeve used in connection with the rod.

Figure 7 is a side elevation partly in section of a slightly modified form of the invention,

45 Figure 8 is a cross-section on the line 8—8 of Figure 7.

Referring more particularly to the drawings the numeral 1 designates the improved grinding mill rod comprising the preferred 50 form of the present invention. This rod is composed of two or more distant pieces having different physical characteristics, there being provided a plurality of replaceable wearing sleeves 2, which are formed from 55 a high abrasive resistant material, such as

manganese steel, while the axially extending core 3 of the rod is formed from a tough, ductile material possessing high tensile strength. It will be understood that these rods are employed in connection with what is known in the art as a grinding mill (not shown). These mills ordinarily comprising large revolving cylinders capable of receiving therein a predetermined quantity of an ore, or some other similar substance which it is desired to pulverize or disintegrate. The rods 1 are placed within the cylinders loosely, so that as the cylinders are rotated, the rods will rise and fall contacting with one another and with the material within the cylinders so that said materials will be crushed and disintegrated by the abrasive action of the rods. Considerable difficulty has been encountered hitherto in the matter of providing a durable and efficient rod, 70 which will not crack or break under ordinary service, and one which is convenient and economical to produce.

It is desirable that a grinding rod of this character should have hardened abrasive 80 resistant surfaces so as to resist the wear which takes place when the rods come into contact with the materials to be disintegrated and with the other rods in the mill cylinders. However, in practice it has been found that if these rods are formed of uniform density and hardened throughout they are so brittle that breakage frequently occurs therein from the stresses to which they are subjected in the revolving cylinders or 85 drums.

To avoid this objection, without losing durability of the hardened abrasive rod, the outside layer, or in this instance the sleeves 2, is manufactured in short cylinders or sleeves 90 and then threaded or stacked on the core 3 which possesses a certain degree of resiliency or flexibility which enables the rod to stand, without breaking, the stresses of 95 service.

Again, prior methods of forming these rods has consisted in casting or rolling the outside layer of high abrasive material on the core of relatively soft or of wrought metal. This method has certain inherent 100 disadvantages, the outstanding of which is that the outside hardened layer of metal will in practice vary in thickness and lack uniformity in diameter throughout the length of the rod. Thus, these rods in wearing 110

down will wear through the outside layer of hard material and following which the core of softer material will be exposed so that wear takes place therein very rapidly, so 5 that the rod will lose its strength and resiliency, permitting of the breaking of the rod and losing the advantage of employing the central core.

Also, when the outside layer is rolled or 10 cast on the core the two materials or metals from which they are formed may vary considerably due to a different relative rate of expansion and contraction during heat treatment. Frequently the internal strains thus 15 set up will also cause the rods to crack and break over during manufacture or after relatively short use thereof.

The present construction eliminates the 20 above mentioned faults or defects in the prior forms of grinding mill rods described. By manufacturing the hard abrasive resistant material in separate sleeves or cylinders and then longitudinally aligning the same on a tough steel rod or core, several very important 25 advantages are obtained. First, the cylinders are of uniform thickness or diameter throughout the length of the rod; second, the core is sufficiently tough to hold the sleeves on the rod during the life of the 30 sleeves and third, a more resilient or elastic rod is provided. In rolling over and over in the drum of a grinding mill, the rod 1 will be amply rigid to stand all of the strains and at the same time accomplish more work 35 upon the material being ground than the ordinary, cold rolled, rigid rods.

There are several different ways of holding the cylinders or sleeves 2 on the inside core 3. In this respect the cores 3 in cross 40 section are preferably of hexagonal form, and are received within the axially disposed hexagonal openings 4 provided in the sleeves or cylinders 2. By this construction the rotation of the sleeves relatively to the core is 45 effectively precluded. However, it will be obvious that many other equivalent forms may be employed for accomplishing this same purpose. Such for example as by means of a key or pin.

50 To prevent longitudinal movement of the

sleeves upon the core 3, the latter in this instance has its ends reduced and threaded as at 5, for the reception of nuts 6 which are positioned within sockets 7 provided in the end sections of the sleeves 2. To prevent 55 rotation of the nut, the threaded extremity 5 of the core 3 may be headed as at 8, or a transverse pin 9 may be used for locking the nuts against rotation. The method employed, however, for holding the sleeves on 60 the rod or core must possess sufficient strength so that the assembled rod with the sleeves can be very roughly handled.

If desired the sleeves 2 may be provided at 65 certain of their ends with longitudinal projections 10, which are adapted to be received within sockets or recesses 11 provided therefor in the complementary ends of adjacent sleeves. This construction results in providing an interlocking connection between the 70 sleeves carried upon a single core, enabling the sleeves to co-ordinate with one another so as to preclude rotary movement thereof on the supporting core. Also, it will be noted that the sleeves may be provided, as shown in 75 Figure 6, with polygonal exterior surfaces 13, instead of the plain cylindrical form. Other changes of a similar nature may be made, of course, without departing from the 80 spirit of the invention as expressed in the following claims.

What is claimed is:

1. A grinding mill rod comprising a steel core, said core being provided with polygonal surfaces, a plurality of high abrasive resistant steel sleeves having axially disposed polygonal sided openings extending therethrough and adapted to receive said core, and fastening appliances provided in connection with the ends of said core normally 90 preventing longitudinal movement of the sleeves on said core.

2. In a device of the character described, an axially extending core, a plurality of sleeves formed from a high abrasive resistant steel mounted upon said core, and interlocking connections between the adjoining end portions of said sleeves.

In testimony whereof I affix my signature,

WALTER B. FLOYD.
